Primary Examiner — Llorellys Martinez-Rivera(74) *Attorney, Agent, or Firm* — Andrew F. Young;
 NOLTE LACKENBACH SIEGEL(57) **CLAIM**

The ornamental design for a frame extrusion, as shown and described.

DESCRIPTION

FIG. 1 is a front top perspective view of a frame extrusion showing my new design.

FIG. 2 is a front bottom perspective view thereof.

FIG. 3 is a right side elevation view thereof.

FIG. 4 is a left side elevation view thereof.

FIG. 5 is a front elevation view thereof.

FIG. 6 is a rear elevation view thereof.

FIG. 7 is a top plan view thereof; and,

FIG. 8 is a bottom plan view thereof.

The extrusion is shown with a symbolic break in its length. The appearance of any portion of the extrusion between the break lines forms no part of the claimed design.
